CLAIM

The ornamental design for a brush attachment for a spray nozzle, as shown and described.

DESCRIPTION

FIG. 1 is a front elevational view of a brush attachment for a spray nozzle embodying my new design, the top plan, bottom plan and rear elevational views being the same as the front elevational view, the portion shown in broken lines forming no part of the inventive design;

FIG. 2 is an exploded view of the design shown in FIG. 1;

FIG. 3 is a right side elevational view thereof;

FIG. 4 is a left side elevational view thereof; and,

FIG. 5 is a view similar to FIG. 1 but showing the brush portion in cross-section.
